UNITED STATES PATENT OFFICE.

JOSEPH SHAW GAUNT AND HARRY DYSON, OF MANCHESTER, ENGLAND.

LAPPET FOR SPINNING AND LIKE MACHINES.

1,302,029.

Specification of Letters Patent. Patented Apr. 29, 1919.

Application filed May 10, 1917. Serial No. 167,680.

To all whom it may concern:

Be it known that we, JOSEPH SHAW GAUNT and HARRY DYSON, of Manchester, in the county of Lancaster, England, have invented certain new and useful Improvements in or Relating to Lappets for Spinning and like Machines, of which the following is a specification.

The object of the present invention is the improvement of lappets and thread guides for spinning and like machines and more particularly to provide improved means of securing firmly in position a removable eyelet, which when cut by the yarn or thread can be easily removed and replaced by a new one.

According to this invention a porcelain or other suitable eye is held in position by means of a resilient bifurcated holder secured to the lappet by a bolt in the usual manner. The eye is suitably formed to fit between the two members of the bifurcated holder and the parts are so arranged that the eye is firmly gripped by the said members being forced together when the holder is secured by the bolt to the lappet. The eyelet may be so formed that the two members of the holder must be pushed apart before the eyelet can be removed as will be further described.

The forward portion of the bifurcated holder can be formed with splayed projections adapted to guide the yarn into the eye and also with laterally extending slots adapted to prevent the yarn from flying out.

The lappet may be secured to the lappet board in any convenient manner, for example, by hinges with elongated holes to permit lateral adjustment.

In order that the invention may be better understood a sheet of drawings is appended in which:—

Figure 1 is a plan view of the bifurcated holder and the lappet.

Fig. 2 is a section on line 2—2 of Fig. 1, and shows the front part of the lappet.

Figs. 3 and 4 show the removable eyelet in sectional plan and elevation.

Fig. 5 is a view similar to Fig. 2, showing a modification.

The same reference characters indicate the same parts in all of the figures.

1 represents a laterally compressible bifurcated holder, formed with a suitable circular opening 2, the sides of which form jaws adapted to receive and grip the porcelain or

other eyelet 12; splayed wings 3, to facilitate the entrance of the yarn, and notches 4, to prevent the yarn from flying out again. The holder is provided with a positioning member, here shown as a recess 5, at the inner ends of said gripping-jaws. The eyelet 12 is provided with the usual yarn-receiving slot 13 at one side, and is provided with a complementary positioning member, here shown as a projection 5^a, adapted to enter the recess 5 and prevent the introduction of the eyelet except in the correct position, said projection being diametrically opposite the slot 13. The bifurcated holder is preferably made of suitable thickness to fit in a corresponding groove 1^a, in the periphery of the eyelet. In the lappet 7 a suitable slot 7^a is formed to receive a bolt 8, said bolt having a head and a nut adapted to exert clamping pressure simultaneously on the lappet and the holder. The rear portion of the holder 1 is provided with a slot 6, through which the bolt also passes so that the holder can be adjusted inward or outward on the lappet so far as the limits of the slot 6 permit. The holder 1 is so formed that its natural spring is not necessarily sufficient to grip the eyelet with the requisite firmness until the holder is fastened to the lappet by the bolt 8. As shown by Figs. 1 and 2, the edge portions 7^b of the lappet are beveled to form an angle greater than a right angle with the sides of the lappet, and the edge portions 9 of the two members of the bifurcated holder 1 are correspondingly beveled. When the bolt 8 is loosened the holder can be adjusted inward or outward as required, and as soon as the bolt is again tightened, the bifurcations of the holder are pressed together by the beveled edge portions and firmly grip the eyelet, the holder being therefore simultaneously secured to the lappet in the required position and caused to grip the eyelet. Other forms than that shown in Fig. 4 may be adapted without departing from the spirit of the invention. For instance, the bolt 8 may be provided with a washer 10 formed with tapered faces 10^a to engage correspondingly tapered edge portions 9^a of the holder, as shown in Fig. 5.

It will be seen that the wings 3 are spaced apart to form a slot or passage permitting the entrance of the yarn into the eyelet, and that the notches 4 are obliquely arranged relatively to said passage and open into the latter. It will also be seen that the position-

ing means including the recess 5 and the projection 5^a, are arranged to hold the yarn-receiving slot 13 of the eyelet in alinement with the thread passage formed by the 5 wings 3.

Claims:

1. In combination, a lappet, a bifurcated laterally compressible holder having opposed eyelet-gripping jaws, and a headed bolt having an adjustable nut and adapted to exert clamping pressure simultaneously on and detachably connect the lappet and holder, holder-compressing means, actuated by said pressure, being provided for laterally compressing the holder.

2. In combination, a lappet having beveled edge portions, a bifurcated laterally compressible holder, having opposed eyelet-gripping jaws and beveled edge portions 20 complementary to the beveled edge portions of the lappet, and clamping means adapted to exert pressure simultaneously on the lappet and holder and at the same time cause said beveled edge portions to coöperate in laterally compressing the holder, and causing said jaws to grip an eyelet.

3. In combination, a lappet having beveled edge portions, a bifurcated laterally compressible holder, having opposed eyelet-gripping jaws and beveled edge portions 30 complementary to the beveled edge portions of the lappet, and a headed bolt having a nut and adapted to exert clamping pressure simultaneously on the lappet and holder and at the same time causes said beveled edge portions to coöperate in laterally compressing the holder, and causing said jaws to grip an eyelet.

4. In combination, a bifurcated eyelet

holder adapted to be secured to a support and 40 formed to project therefrom, said holder having eyelet-gripping jaws, an eyelet-positioning member at the inner portions of said jaws, and wings projecting outwardly from the jaws, said wings being spaced apart 45 to form a threaded passage, and an eyelet formed to be gripped by said jaws and having a yarn-receiving slot at one side, and a positioning member complementary to the first-mentioned positioning member and diametrically opposite said slot, whereby the eyelet slot is held in alinement with said thread passage.

5. In combination, a bifurcated eyelet holder adapted to be secured to a support 55 and formed to project therefrom, said holder having eyelet-gripping jaws, an eyelet-positioning member at the inner portions of said jaws, and wings projecting outwardly from the jaws, said wings being spaced 60 apart to form a thread passage, and an eyelet formed to be gripped by said jaws and having a yarn-receiving slot at one side, and a positioning member complementary to the first-mentioned positioning member and 65 diametrically opposite said slot, whereby the eyelet slot is held in alinement with said thread passage, said wings being provided with oblique notches opening into said thread 70 passage and adapted to prevent the yarn from flying out.

In testimony whereof we have affixed our signatures in presence of two witnesses.

JOSEPH SHAW GAUNT.
HARRY DYSON.
